(57) **CLAIM**

The ornamental design for a car door protector, as shown and described.

DESCRIPTION

FIG. 1 is a front, right and top perspective view of a car door protector showing my new design;

FIG. 2 is a rear, left and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown in the figures are for the purpose of illustrating portions of the car door protector that forms no part of the claimed design.
